PERFORATING GUN WITH SERIAL FIRING
MEANS

Ira J. McCullough, Los Angeles, Calif.

Application February 10, 1940, Serial No. 318,297

12 Claims. (Cl. 164—0.5)

My invention relates to means for perforating casing while it is in place within a well, and relates in particular to a gun perforator whereby the perforation of the casing or casings is accomplished by firing projectiles therethrough.

It is an object of the invention to provide a perforating gun of simple character which may be made small enough to pass through an oil tube set in a well casing without sacrifice of operating efficiency and wherein maximum force of the explosive charge is obtained without sacrifice of other qualities, including simplicity of manufacture of the gun, relative ease of loading and reloading and positive firing of all of the powder charges with which the gun is loaded.

It is an object of the invention to provide a perforating gun wherein the explosive charge, associated with a gun bore carrying the projectile, is ignited by a blast of gaseous combustion products produced from the burning of a charge of powder in a separate chamber and delivered to the chamber containing the explosive through a passage of relatively small diameter, which may be referred to as the ignition passage, a particular feature of the invention being the provision of valve means which prevents reverse flow of gas through the ignition passage, thereby reducing to substantially minimum the loss of pressure resulting from the burning of the propelling charge of explosive associated with the gun bore.

The present invention contributes in the making of a perforating gun of relatively high efficiency but of relatively small diameter. As the diameter of the gun body is reduced, the dimension of other of the parts must be likewise reduced, including the diameter of the powder chamber which connects to the inner end of the gun bore. The size of this powder chamber places restrictions upon the quantity of explosive which may be employed. My present invention makes it possible to obtain near to maximum propelling effect from the gaseous combustion products resulting from the firing of a charge of given size.

It is a further object of the invention to provide a perforating gun of the character set forth in the foregoing wherein the gun bores and powder chambers are serially arranged, the powder chambers being serially connected by ignition passages wherein a small part of the gas resulting from the burning of one powder charge is transmitted to the succeeding powder charge to cause the combustion of the succeeding powder charge, each of these ignition passages having associated check or closure valve means for pre-

venting reverse flow of gas therethrough. Accordingly, the firing of a charge in the first chamber of the gun results in the serial firing of all of the charges.

5 5. A further object is to provide a simple valve means of the character described placed so that it will permit passage of gas through an ignition passage into a chamber and will be effectively closed by pressure of gas in such chamber resulting from the firing or burning of the charge therein.

10 15. A further object of the invention is to provide a simple check or closure valve having associated means for urging it toward closed relation to a valve orifice forming a part of the ignition passage of the gun.

15 Further objects and advantages of the invention will be brought out in the following part of the specification.

20 Referring to the drawing which is for illustrative purposes only:

Fig. 1 is a view of a gun body sectioned on a medial plane, showing a preferred form of my invention.

25 Fig. 2 is a cross-section taken on the plane indicated by the line 2—2 of Fig. 1.

Fig. 3 is an enlarged fragmentary cross-section showing a check or closure valve having a spring to urge the same toward closed relation.

30 Fig. 4 is an enlarged fragmentary sectional view of an alternative form of valve wherein the closure member is yieldably held in engagement with the valve seat.

35 Fig. 5 is an enlarged fragmentary sectional view to show the space between the valve closure and seat of Fig. 1.

For the purpose of illustrating a simple embodiment wherein the invention may be practiced, I have in Fig. 1 shown that portion of a 40 gun body 10 with which the present invention is concerned. This gun body 10 includes a plurality of cylindrical sections 11 which are arranged in consecutive order below an upper section 12 which may be formed and suspended from a cable in the general manner shown in my Patent No. 2,218,802, granted October 22, 1940, and my copending application Serial No. 304,333. It will be understood that the sections 11 and 12 may be secured together in any suitable manner. For connecting these sections together in axial alignment I prefer to employ threaded tool joints, and accordingly I have shown the sections 11 each provided with a threaded box or tapered counter-bore 13, at the upper end thereof, and have shown

the sections 11 and 12 with cooperating downwardly extending threaded pins 14.

The body sections 11 are provided with gun bores 15 formed in barrels 16 which are threaded into bores 17 in the gun body 11. An elongated powder chamber 18 communicates with the inner end of each bore 17 and accordingly with the inner end of each gun bore 15. In each chamber 18 a suitable powder charge 19 is placed, and the gas pressure resulting from the combustion of the charges 19 is employed to discharge projectiles 20 at high velocity from the gun bores 15. In the use of the term "powder charge" I intend the inclusion of all explosives suitable for use in the manner described. The powder charge chambers 18 are serially connected in such a manner that the combustion or burning of a charge 19 in one of the chambers will result in the firing of the charge in the succeeding chamber of the series, whereby a serial firing of all of the powder charges will be accomplished.

The upper section 12 has a bore 21 leading downward from the upper end thereof, and extending downwardly from the bottom of the bore 21 there is a chamber or bore 22 to receive a priming cap or firing cartridge 23. A firing pin 24 is supported for axial movement in the bore 21 by a threaded bushing 25, the lower end of this firing pin 24 having a head 26 from which a point 27 projects downward for engagement with the head of the cartridge 23 when the firing pin 24 is driven down. A removable valve seat member 28 may be secured in the lower end of each threaded pin 14, and an ignition passage 29 of relatively small diameter is extended down from the bore 22 through the pin 14 and through the valve seat 28.

In each body section 11 a valve chamber 30 is formed in the bottom of each threaded box 13, to communicate with the upper end of each powder chamber 18. Each gun body section 11 has an ignition passage 31 which extends downward from the lower end of a powder chamber 18 and through a pin 14 and a valve seat member 28. To restrain the downward passage of gas therethrough, the passage 31 has at least a portion thereof, such as the upper section 32, made to small diameter.

In each valve chamber 30 I place a valve closure member 33 comprising a cylindrical body 34 having an upwardly projecting conical point 35 to engage a cooperating valve seat 36 formed in a valve seat member 28. The cylindrical member 34 has openings 37 extended from the upper to the lower end thereof, these openings being shown in the form of radial slots, the inner walls 38 of which converge downwardly. These slots 37 cooperate with other passages shown and described to form passage means connecting the chambers of the device which contain the explosives. For example, the upper bore 22 which receives the cartridge 23 constitutes a chamber for the explosive contained in the cartridge 23. Such chamber 23 is connected with the next downwardly consecutive powder chamber 18 by passage means consisting of the passage 29, the space 40 in the upper chamber 30 and the grooves or slots 37 of the cylindrical member 34. Adjacent powder chambers 18 are connected by passage means comprising a passage 31 and the space within a valve chamber 30 not filled by the contained closure member 33. The height of the closure member 33 is such that when it rests on the bottom wall of the chamber 30 in which it is contained, there will be, as shown in Fig. 5, a

small space or orifice 35' between the conical point 35 and the valve seat 36.

In the operation of the gun, with the cooperating parts assembled as shown in Fig. 1, the firing pin 24 is driven down to bring the point 27 into engagement with the cartridge 23. The combustion products from the cartridge 23 pass downward through the passage 29 and around the valve closure member 33 into the upper powder chamber 18 to set off the charge 19 in such chamber 18. The gaseous products from the burning of the charge 19 in the upper chamber 18 immediately produce a high pressure with the result that the upper valve closure member 35 is lifted into engagement with the seat 36. When the gas pressure in the upper chamber 18 reaches such high value as to shear off the plate 45 which holds the upper projectile 20 in its gun bore 15, the projectile will be discharged at high velocity. The upper valve, comprising the closure member 35 prevents the high pressure resulting from the relatively heavy charge 19 from passing up through the passage 29 and the bore 22 and exerting its force against the lower end of the firing pin 26, thereby relieving the firing pin 24 from danger of being bent by end thrust applied thereto.

Some of the gas produced in the upper chamber 18 as the result of the burning of a charge 19 therein passes down through the passage 31 and past the valve closure member 33 lying at the lower end thereof, into the succeeding powder chamber 18, thereby causing ignition of the second charge 19. The second valve closure member 33 prevents a reverse flow of gas from the second chamber 18 through the passage 31, so that there can be no escape or loss of the products resulting from the firing of the second charge 19, thereby assuring that the full force of the products of the explosion of the second charge 19 will be usefully applied in discharging the second projectile 20 and transmitting the ignition effect through the succeeding passage 31 to the succeeding powder chamber, which is not shown for the reason that it is merely a duplication of the powder chambers 18 shown and described.

In Fig. 3 I show a valve chamber 30' of essentially the same character and having the same position as the valve chamber 30 of Fig. 1, in which a valve closure member 33' is operatively disposed. This valve member 33' differs from the valve member 33 previously described in having the lower portion 46 thereof reduced in diameter so as to leave an annular space 47 within the lower part of the chamber 30' below a shoulder 48 intermediate the ends of the valve closure member 33'. For passage of gas from the upper end to the lower end of the chamber 30' the valve closure member 33' is provided with a plurality of openings 37' which are spaced around the conical valve projection 35' of the member 33'. A spring 49 in the space 47 operates in compression to exert a yielding force in upward direction to hold the conical projection 35' in engagement with the valve seat 36.

In Fig. 4 I show a form of my invention wherein a conical valve closure 50 is formed in the center of a disc 51 which fits into a recess 52 formed in downwardly projecting relation in the bottom of a box 13 of a section 11. The bottom wall 53 of the disc 51 is recessed as shown so that only a peripheral area 54 of the bottom wall of the disc 51 will engage the bottom wall 55 of the recess 52. The conical closure member 50 is so formed with relation to the remaining portion of

the disc 51 that it will be yieldably maintained in engagement with a valve seat 56 formed in a valve plate 57 which rests in the upper part of the recess 52 and is clamped in place by the lower end of a pin 14. A plurality of openings 58 are spaced around the closure member 50 for passage of gas downward into the upper part of a powder chamber 18 which extends downward from the recess 52 as shown. When an ignition gas is applied through an ignition passage, such as the passage 31, the force thereof will move the closure member 50 downward, since the central portion of the disc 51 is so formed that it may be flexed downward when sufficient pressure is applied, permitting the ignition gas to pass between the closure member 50 and the valve seat 56, and thence through the opening 58 into the chamber 18. When the gas pressure above and below the closure member 50 is equalized, the closure member 50 will be returned to engagement with the valve seat 56 by resilience of the disc 51 which tends to hold the closure member 50 in the condition thereof shown in Fig. 4.

Although I have shown and described simple and practical forms of my invention, it will be understood that certain parts or elements thereof may be replaced by other equivalent parts or elements without departing from the spirit of the invention. Accordingly, the invention is not to be limited by the details of this disclosure but should be accorded full scope of the following claims.

I claim as my invention:

1. In a perforating gun of the character described, the combination of: a body having gun bores therein to receive projectiles, a plurality of powder chambers and passage means serially connecting said chambers so that ignition will be transmitted serially from one chamber to another; a powder charge in each of said chambers; means for setting off one of said powder charges; and check valves in said passage means to prevent reverse flows of gas therethrough.

2. In a perforating gun of the character described, the combination of: a body having a gun bore, a powder charge chamber connected to said gun bore, and an ignition passage connected to said chamber; means for passing an ignition gas through said passage into said chamber; and valve means associated with said passage for preventing a reverse flow of gas therethrough.

3. In a perforating gun of the character described, the combination of: a body having a gun bore, a powder chamber connected to said gun bore, a second powder chamber spaced from said first chamber, and an ignition gas passage connecting said first and second chambers; powder charges in said chambers; means for setting off the powder charge in the first of said chambers; and closure valve means associated with said passage for preventing a reverse flow of gas from said second chamber to said first chamber.

4. In a perforating gun of the character described, the combination of: a body having a gun bore, a powder chamber connected to said gun bore, a second powder chamber spaced from said first chamber, and an ignition gas passage connecting said first and second chambers; powder charges in said chambers; means for setting off the powder charge in one of said chambers, a portion of the gaseous products therefrom passing through said passage to set off the powder charge in the other of said chambers; and check valve means associated with said passage for prevent-

ing reverse flow of gas through said ignition gas passage.

5. In a perforating gun of the character described, the combination of: a body having serially arranged gun bores and cooperating chambers to receive powder charges; means to ignite a powder charge in at least one of said chambers; and walls forming passages serially connecting said chambers through which ignition gas may pass consecutively from each of said chambers to the next; and check valve means for said passages operative to prevent reverse flow of ignition gas therethrough.

10 6. In a perforating gun of the character described, the combination of: a body having a gun bore, a first powder chamber connected to said gun bore, a second powder chamber spaced from said first powder chamber, and passage means connecting said first and second chambers; a firing charge in each of said chambers; and valve means for said passage means for preventing reverse flow of gas therethrough.

15 7. In a perforating gun of the character described, the combination of: a body having a gun bore, a first powder chamber connected to said gun bore, a first powder chamber connected to said gun bore, a second powder chamber spaced from said first powder chamber, and passage means connecting said first and second chambers; a firing charge in each of said chambers; and check valve means for said passage means comprising walls forming a valve orifice and a closure member positioned so as to permit a forward flow of gas from one of said chambers to the other of said chambers, and to close said orifice against a reverse flow of gas through said passage means.

20 8. In a perforating gun of the character described, the combination of: a body having a gun bore, a first powder chamber connected to said gun bore, a second powder chamber spaced from said first powder chamber, and passage means connecting said first and second chambers; a firing charge in each of said chambers; and check valve means for said passage means comprising walls forming a valve orifice and a closure member movably supported in cooperative relation to said orifice so as to be moved by pressure of gas from said first chamber toward said second chamber into closing relation to said orifice.

25 9. In a perforating gun of the character described, the combination of: a body having a gun bore, a first powder chamber connected to said gun bore, a second powder chamber spaced from said first powder chamber, and passage means connecting said first and second chambers; a firing charge in each of said chambers; and check valve means for said passage means comprising a valve seat facing toward said first chamber and defining an orifice forming a part of said passage means, and a closure member yieldably held in closing relation to said seat.

30 10. In a perforating gun of the character described, the combination of: a body having a gun bore, a first powder chamber connected to said gun bore, a second powder chamber spaced from said first powder chamber, and passage means connecting said first and second chambers; a firing charge in each of said chambers; and check valve means for said passage means comprising a valve seat facing toward said first chamber and defining an orifice forming a part of said passage means, a closure member to engage said valve seat, and means yieldably holding said closure member in engagement with said valve seat.

35 11. In a perforating gun of the character described, the combination of: a body having a

gun bore, a first powder chamber connected to said gun bore, a second powder chamber spaced from said first powder chamber, and passage means connecting said first and second chambers, said passage means including a valve chamber and a valve seat forming a valve orifice at the end of said valve chamber toward said second powder chamber; and a valve body movably disposed in said valve chamber so as to move to and from said valve seat, said valve body having a closure element to engage said valve seat and being so formed with relation to the walls of said valve chamber as to provide space for passage of gas from end to end of said valve chamber.

12. In a perforating gun of the character described, the combination of: a body having a

gun bore, a first powder chamber connected to said gun bore, a second powder chamber spaced from said first powder chamber, and passage means connecting said first and second chambers, 5 said passage means including a valve chamber and a valve seat forming a valve orifice at the end of said valve chamber toward said second powder chamber; and a valve body movably disposed in said valve chamber so as to move to and from said valve seat, said valve body having a closure element to engage said valve seat and having openings from end to end thereof for passage of gas freely from one end to the other of said valve chamber.

IRA J. McCULLOUGH.
